US00D963289S

(12) United States Design Patent (10) Patent No.: US D963,289 S
Wormgoor (45) Date of Patent: * Sep. 13, 2022

(54) GARMENT

(71) Applicant: LULULEMON ATHLETICA CANADA INC., Vancouver (CA)

(72) Inventor: Kim Bernice Wormgoor, Vancouver (CA)

(73) Assignee: LULULEMON ATHLETICA CANADA INC., Vancouver (CA)

(*) Notice: Patent file contains an affidavit/declaration under 37 CFR 1.130(b).

() Term: 15 Years

(21) Appl. No.: 29/746,025

(22) Filed: Aug. 11, 2020

(51) LOC (13) Cl. 02-01

(52) U.S. Cl.
USPC D2/706

(58) Field of Classification Search

USPC D2/702, 703, 706-710, 718-727, 731,
D2/737, 739

See application file for complete search history.

(57) CLAIM

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a front view thereof shown in an environment of use; and,

FIG. 8 is a rear view thereof shown in an environment of use. The portions of the garment shown in broken lines in FIGS. 2, 6, and 8 do not form part of the claimed design. The broken line showing of the arms, torso, neck, and head in FIGS. 7 and 8 is for the purpose of illustrating portions of the environmental structure and forms no part of the claimed design.

1 Claim, 8 Drawing Sheets
